(57) **CLAIM**

The ornamental design for a fixed mount thermal camera, as shown and described.

DESCRIPTION

FIG. 1 is a top, front, right perspective view of a fixed mount thermal camera showing our new design.

FIG. 2 is a bottom, rear left perspective view thereof.

FIG. 3 is a front elevation view thereof.

FIG. 4 is a right side elevation view thereof.

FIG. 5 is a top plan view thereof.

FIG. 6 is a left side elevation view thereof.

FIG. 7 is a rear elevation view thereof; and,

FIG. 8 is a bottom plan view thereof.

The broken lines illustrate portions of the fixed mount thermal camera in which the design is embodied that form no part of the claimed design.
